(57) **CLAIM**

What is claimed is; the ornamental design for, a rear gate for a truck vehicle, as shown and described.

DESCRIPTION

FIG. 1 is a front perspective view of a rear gate for a truck vehicle, showing our new design;

FIG. 2 is a rear perspective view thereof;

FIG. 3 is a front elevation view thereof;

FIG. 4 is a rear elevation view thereof;

FIG. 5 is a top plan view thereof;

FIG. 6 is a bottom view thereof;

FIG. 7 is a right side elevation view thereof; and,

FIG. 8 is a left side elevation view.

The broken lines shown throughout the drawing are for illustrative purposes only and form no part of the claim design.
